UNITED STATES PATENT OFFICE

136,966

DESIGN FOR A TOY AIRPLANE OR SIMILAR ARTICLE

Paschal Wolf Winer, Great Neck, N. Y.

Application October 16, 1943, Serial No. 111,403

Term of patent 7 years

To all whom it may concern:

Be it known that Paschal Wolf Winer, a citizen of the United States and resident of Great Neck, in the county of Nassau and State of New York, has invented a new, original, and ornamental Design for a Toy Airplane or Similar Article, of which the following is a specification, reference being had to the accompanying drawing, forming part thereof, and in which,

Fig. 1 is a side elevational view of the toy airplane, embodying my new design;

Fig. 2 is a top plan view;

Fig. 3 is a bottom plan view; and

Fig. 4 is a front elevational view.

I claim:

The ornamental design for a toy airplane or similar article, substantially as shown.

P. WOLF WINER.
